(57) **CLAIM**

The ornamental design for a lighted sign, as shown and described.

DESCRIPTION

FIG. 1 is an upper perspective view of the lighted sign showing my design.

FIG. 2 is a front elevation view thereof;

FIG. 3 is a back elevation view thereof;

FIG. 4 is a top plan view thereof;

FIG. 5 is a bottom view thereof;

FIG. 6 is a side elevation view thereof;

FIG. 7 is an opposite side elevation view thereof; and,

FIG. 8 is an inverted perspective view thereof, showing an open panel configuration with broken line electronics structures.

The broken line structures are presented for illustrative purposes and for no part of the claimed design.
